Primary Examiner — George D. Kirschbaum*Assistant Examiner* — Natasha Vujcic(74) *Attorney, Agent, or Firm* — Carter DeLuca Farrell & Schmidt, LLP(57) **CLAIM**

The ornamental design for a lighting apparatus, as shown and described.

DESCRIPTION

FIG. 1 is a front, perspective view of a lighting apparatus showing our new design, according to a first embodiment; FIG. 2 is a front side elevation view thereof;

FIG. 3 is a back elevation view thereof;

FIG. 4 is a left side elevation view thereof;

FIG. 5 is a right side elevation view thereof;

FIG. 6 is a bottom elevation view thereof;

FIG. 7 is a top elevation view thereof.

FIG. 8 is a front, perspective view of a lighting apparatus showing our new design, according to a second embodiment;

FIG. 9 is a front side elevation view thereof;

FIG. 10 is a back elevation view thereof;

FIG. 11 is a right side elevation view thereof;

FIG. 12 is a left side elevation view thereof;

FIG. 13 is a top elevation view thereof;

FIG. 14 is a bottom elevation view thereof; and,

FIG. 15 is a front perspective view of the claimed designs shown in FIGS. 6 and 14.

The broken lines shown are included for the purpose of illustrating a portion of the lighting apparatus that form no part of the claimed design.
